UNITED STATES PATENT OFFICE.

JOHN H. WHITE AND CHARLES A. WERNER, OF BERKELEY, CALIFORNIA.

TOWEL RACK.

Application filed July 19, 1920. Serial No. 397,459.

To all whom it may concern:

Be it known that we, JOHN H. WHITE and CHARLES A. WERNER, citizens of the United States, residing at Berkeley, in the county 5 of Alameda and State of California, have invented certain new and useful Improvements in Towel Racks, of which the following is a specification.

This invention relates to towel racks, and 10 has for its object the provision of a rack in which a towel will be securely held from falling down and becoming soiled.

Another object is to provide a towel rack which is simple in construction and may be 15 cheaply manufactured.

Referring to the drawing which forms a part of this specification, and in which:

Figure 1 is a perspective view of our towel rack.

20 Figure 2 is a side view of one of the holders.

Figure 3 is a front view of one of the wall brackets, with the holding arm removed.

25 Referring more particularly to the drawing: The towel rack comprises two holding units 1 and 2, which consists of horizontal holding arms 3 and 4. The arms 3 and 4 are pivotally secured to wall brackets 5 and

30 6. A U-shaped spacing bar 7 is secured to the arms 3 and 4, the purpose of which is to cause the two arms to swing together and to always maintain the same distance between them.

Secured to the bottom of the arms 3 and 4 35 are a plurality of yieldable spring clamps 8, which are formed U-shape of a single piece of metal. At a point slightly above the bottom of the clamps 8, an inward bend is formed so that the two legs touch, to 40 form an effective clamp for the edge of the towel. The towel is held by being forced between two opposite clamps on the arms 3 and 4.

The wall brackets 5 and 6 consist of plates 45 9 and 10 which are secured to the wall, and U-shaped supports 11 and 12 are secured to the plates 9 and 10 by means of clips 13 and 14, formed in said plates and bent over the intermediate members of said supports 50 which members rest against said plates.

Having described our invention, we claim:

A towel rack including an octagonal plate having holes inserted therethrough whereby the plate may be attached to a wall, inwardly extending slots from two opposite sides of the plate, the part between the slots being turned up to form clips, a flat U shaped support attached to the plate by means of the clip being bent over the intermediate member of the support, a holding arm pivoted to said support between the arms thereof, and clamps on said holding arm for holding the towels.

In testimony whereof we affix our signatures.

JOHN H. WHITE.
CHARLES A. WERNER.
